UNITED STATES PATENT OFFICE

ARTHUR R. GROSS, OF ST. PAUL, MINNESOTA, ASSIGNOR, BY MESNE ASSIGNMENTS, TO TRUSSBILT STEEL DOORS, INC., OF ST. PAUL, MINNESOTA, A CORPORATION OF DELAWARE

HOLLOW SHEET-METAL UNIT AND PROCESS OF PRODUCING THE SAME

Application filed September 15, 1927. Serial No. 219,642.

My present invention relates to a hollow sheet metal unit having an internal reinforcement secured thereto by spot welding, and the process of producing the same, and has 5 for its object to provide such a unit that is of relatively light weight, strong and rigid and has the joints between its sections and between the unit and the reinforcement filled to deaden sound thus eliminating metallic 10 ring.

The invention, while intended for general use in the construction of table tops and panels in building structures, car bodies and the like, is especially well adapted in the 15 construction of doors and is so illustrated and described in the present application.

To the above end, generally stated, the invention consists of the novel devices and combinations of devices hereinafter described and 20 defined in the claim.

In the accompanying drawings, which illustrate the invention, like characters indicate like parts throughout the several views.

Referring to the drawings:

25 Fig. 1 is a view partly in side elevation and partly in vertical section, with some parts broken away, illustrating the improved door, and an apparatus for carrying out the improved process;

30 Fig. 2 is a fragmentary view partly in side elevation and partly in section showing one end of the door and the attached hanger bar;

Fig. 3 is an end view with some parts sectioned on the line 3—3 of Fig. 2;

35 Fig. 4 is a fragmentary perspective view showing one corner of the door;

Fig. 5 is a fragmentary detail view principally in section taken on the line 5—5 of Fig. 2;

40 Fig. 6 is a perspective view of one of the T-bolts;

Fig. 7 is a perspective view of one of the spacing blocks;

45 Fig. 8 is a view in section taken longitudinally through a section of the door and illustrating the coating material applied thereto; and

Fig. 9 is a transverse section taken on the 50 line 9—9 of Fig. 8.

The numeral 10 indicates a hollow sheet

metal unit or door comprising a pair of laterally spaced plates 11, the longitudinal edge portions of which are bent laterally toward each other and connected by joints 12 to form the longitudinal edges 13 of said door. The ends of the door 10 are closed by channel end pieces 14 fitted therein with their flanges turned outward and spot welded at 15 to the plates 11. Longitudinal slots 16 are formed in each end of each end piece 14, to afford liquid filling and drain holes, for a purpose that will presently appear.

Within the door 10 is a truss structure 17 for the plates 11 and comprises a corrugated sheet metal plate. The apexes of the corrugations in the truss structure 17 are flat, alternately and directly engage the inner faces of the plate 11 and are spot welded thereto at 18.

The longitudinal edges of the truss structure 17 are shaped to form portions of the joints 12 and which joints are preferably of the type disclosed and broadly claimed in my co-pending application entitled "Metal door structure", filed June 13, 1927, under Serial No. 198,488. It is important to note that the truss structure 17 terminates short of the end pieces 14 and thus leaves a shallow chamber 19 in each end of the door with which the respective ends of the tubular sections in the truss structure 17 formed by the corrugations therein have communication and into which chambers the slots 16 open.

The apparatus used in treating the door 10 to coat the same with a paint or other liquid coating material consists of a relatively deep and narrow tank 20, the top of which is substantially flush with the floor 21 and which tank contains a paint or other coating material α . An overhead track 22 is secured to suitable supports not shown, and extends transversely over the tank 20. A carriage 23 is mounted on the track 22 and has a block and tackle 24 mounted thereon and including a hook 25. Removably attached to the hook 25 is a beam 26 having at its intermediate portion an eye 27 located slightly off center so as to hold said beam inclined, as shown in Fig. 1. A pair of hooks 28 are flexibly at-

tached one to each end of the beam 26 by short rods 29.

For obliquely suspending the door 10 from the beam 26 by the hooks 28 edgewise in a horizontal position there is provided a pair of channel hanger bars 30 detachably secured to the ends of the door 10 by pairs of nut-equipped T-bolts 31 which extend through longitudinal slots 32 in the webs of said bars 10 and through holes in the webs of channel spacing blocks 33. The webs of the spacing blocks 33 bear against the webs of the bars 30, and the flanges of said blocks 33 bear against the webs of the end piece 14 as bases of resistance. These spacing blocks 33 hold the bars 30 in the plane of the door 10 and slightly spaced from the ends thereof.

The heads of the T-bolts 31 are adapted to be inserted through the slots 16 and turned, 20 as shown by broken lines in Fig. 3, to span said slots and engage the inner faces of the end pieces 14 to secure said bolts to the door 10. The length of the heads of the bolts 31 is such that they cannot turn completely 25 around in the compartments 19 and thereby engage the plates 11 and hold the bolts 31 from turning when operating the nuts thereon. It is important to note that the bars 30 are somewhat longer than the width 30 of the door 10 so that their lower ends serve as legs and their upper ends engage a wall or other support to hold said door in an inclined position out of contact with any supporting member after the same has been dipped in the 35 coating material α so that said material may dry without being touched.

In the ends of certain of the flanges of the channel hanger bars 30 are holes 34 through the upper of which the hooks 28 may be inserted to hold the door 10 suspended, as 40 shown in Fig. 1. With the door thus suspended, the same may be lowered into the tank 20 and submerged in the liquid material α . While the door 10 is submerged in the 45 liquid material α , said material will enter the hollow door through the lowermost slots 16 and the air in said door will escape through the slot 16 in the uppermost corner of the door. As the compartments 19 afford com- 50 munication between all of the tubular sections in the truss structure 17, the material α , upon entering said compartments, will completely fill the entire truss structure and coat the entire interior of the door 10. Capillary 55 attraction will draw the material α into all of the joints between the different sections of the door 10 and the joints between the truss structure 17 and the door. It will be noted, by reference to Fig. 3, that the bolts 31 and 60 spacing blocks 33 do not interfere with the passage of the material through the slots 16 and that said material covers the entire door 10 with the exception of very small areas covered by the heads of the bolts 31 and the 65 flanges of the spacing blocks 33.

After the door 10 has been submerged in the material α and left a sufficient length of time for the material α to completely cover the same and enter all of the joints in the door and the truss structure, the door 10 is lifted 70 from the tank 20 and held suspended to allow the surplus material α to drain back into the tank 20 through the slot 16 in the lower corner thereof. The inclined position in which the door 10 is held during the draining thereof prevents the accumulation of a surplus of said material on any spot or parts of the door 10. After the surplus material has been drained from the door 10, the same is handled by means of the bars 30 while detaching the hooks 28 from said bars and placed in position to dry, and during this time the bars 30 hold the door 10 out of contact with any support or object so that the finish thereon is not marred by being touched. 75

After the coating material on the door 10 is dry, the exterior thereof may be finished with any suitable paint, enamel, or other surfacing material and then said finish baked thereon, in any well known manner. This 80 dipping of the door, as previously stated, completely fills all joints between the different sections of the door and its truss structure and when dry the complete door unit is substantially an integral structure, thus preventing vibration, deadening sound and thus 85 eliminating metallic ring. The external coating material on the door 10 is indicated by y and the internal coating material on said door is indicated by z , as shown in Figs. 8 and 9. Fig. 8 clearly illustrates, in an exaggerated manner, how the joints between the truss structure 17 and the plates 11, where they are connected by the spot welding 18, are filled by the material. 90

What I claim is:

A hollow sheet metal unit having open ends, end members fitted in the open ends of the unit and closing the same, said end members having vent and drain holes, and an internal reinforcing member within the unit and transversely dividing the same into a plurality of longitudinally extended hollow sections having open ends, said reinforcing member terminating short of the end members to leave a chamber between each end member and the reinforcing member, the open ended hollow sections affording communication between the chambers. 95

In testimony whereof I affix my signature. 100
ARTHUR R. GROSS.
